CLAIM

The ornamental design for a housing for antenna feed horn and transmit electronics, as shown and described.

DESCRIPTION

FIG. 1 is a side view of a housing for antenna feed horn and transmit electronics in an environment, showing our new design;

FIG. 2 is a perspective view of the housing according to our new design;

FIG. 3 is a side view thereof;

FIG. 4 is a front view thereof;

FIG. 5 is a back view thereof;

FIG. 6 is a top view thereof; and,

FIG. 7 is a bottom view thereof.

The broken line showing of the dish antenna in FIG. 1 is for illustrative purposes only and forms no part of the claimed design.

The broken away showing of the conduit indicates that it is of indeterminate length.
